UNITED STATES PATENT OFFICE.

ALFRED G. CRIPPS, OF AKRON, OHIO, ASSIGNOR TO THE PRUDENTIAL HEATING COMPANY, OF AKRON, OHIO, A CORPORATION OF OHIO.

FIRE-POT.

No. 843,795.

Specification of Letters Patent.

Patented Feb. 12, 1907.

Application filed October 20, 1906. Serial No. 339,809.

To all whom it may concern:

Be it known that I, ALFRED G. CRIPPS, a citizen of the United States, residing at Akron, in the county of Summit and State of Ohio, have invented new and useful Improvements in Fire-Pots, of which the following is a specification.

This invention relates to fire-pots for boiler or warm-air furnaces; and the object thereof is to produce a simple and effectual device of the class described so constructed as to evenly and perfectly distribute the necessary oxygen to the burning fuel and which will permit of the ready removal and replacement of those parts of the device which by reason of the intensity of the fire are most frequently burned out.

A further object of this invention when used in connection with a steam or hot-water boiler is to locate the fire in as close proximity to the boiler-surface as possible and to increase the amount of boiler-surface exposed to the action of the fire as much as the limitations of a device of this kind will permit.

With the foregoing and other objects in view the invention consists of the novel construction, combination, and arrangement of parts constituting the invention to be herein-after referred to, and illustrated in the accompanying drawings, which form a part of this specification, in which is shown the preferred embodiment of the invention; but it is to be understood that changes, variations, and modifications can be resorted to which come within the scope of the claims hereunto appended.

In the drawings, in which similar reference-numerals indicate like parts in the different figures, Figure 1 is a perspective view of the lower portion of the fire-pot of a boiler containing my invention, with portions thereof omitted to better illustrate the construction of the balance. Fig. 2 is a vertical section view of the fire-pot of a boiler, showing the internal arrangements of parts with respect to each other.

In the drawings the reference-numeral 1 designates the ash-pit of the device, which is provided with a clean-out door 2 and has in its upper portion a preferably cylindrical opening 3, surrounded by a seat 4, inclosed by an upwardly-extending flange 5.

On the seat 4 is mounted the lower end of a boiler, (designated by the reference-numeral

6,) or in the case of a hot-air furnace the fuel-section of a furnace is similarly mounted. In order to offer as much of surface of the boiler to the action of the fire, I customarily form the interior thereof with a plurality of upwardly-extending and preferably parallel ribs 60 or undulations 7, so that the spaces existing between these ribs or corrugations will constitute means for the passage of air upwardly around and through the mass of burning fuel supported in the fire-pot. These ribs 7 do 65 not extend to the seat 4, but terminate a short distance above, thereby forming a shoulder or inset portion 8. The portion of the boiler above the shoulder 8 constitutes the upper portion of the fire-pot of this device, and the lower portion thereof is formed as follows: Attached to the inner surface of the seat 4 by suitable holdfast devices 9 is a ring 10, provided at the determinate intervals with inwardly-projecting lugs 11, the 75 inner ends of which are provided with a pair of holes 12, and at points equidistant between lugs 11 the ring 10 is further provided with inwardly-projecting lugs 13 for a purpose to be later described. That portion of 80 a fire-pot of this device which exists below the shoulder 8 is constructed of a plurality of segmental sections 18, each of which has a plurality of slots extending upwardly from its base a sufficient distance to form between 85 them a plurality of downwardly-extending teeth 14. The two outer teeth, as well as the middle tooth of each section, are elongated, and the outer teeth of each section are adapted to enter and rest in the oppositely-disposed openings 12 in adjacent lugs 11, and the middle tooth of each section is adapted to rest on the centrally-disposed lugs 13, thereby securing and holding each section accurately in position and against unintentional displacement. 95

The openings 12 in each lug 11 are spaced apart sufficiently to slightly separate the opposing ends of adjacent sections in order to permit the ready removal and replacement 100 of any one of these sections at any time. The openings 12 in the lugs 11 are situated such a distance inwardly from the edge of the opening 3 in the top of the ash-pit 1 that a sufficient space exists for the passage of air 105 upwardly between the wall of the boiler-section and the rear face of the fire-pot sections, thus permitting oxygen to pass through this

passage and upwardly between the ribs 7 to the point of combustion in the fire-pot.

The fuel in the fire-pot is customarily supported by a rotatable grate 15, provided with a central draw-gate 16, operated by an ordinary handle 17; but as the construction of the grate forms no part of this invention a further description of the same is believed to be unnecessary to the perfect understanding 10 of this invention.

It will be noted that the construction just given affords a free and perfect means for sustaining the mass of fuel in the fire-pot immediately adjacent the lower portion of the 15 boiler-section, and at the same time a perfectly even and continuous supply of oxygen may be supplied to the fuel at all times. It will be further noted that if at any time any one of the fire-pot sections becomes worn or 20 burnt out they may be removed and new ones substituted without the necessity of dismounting the boiler-section, access being readily had to the interior of the fire-pot through the ordinary door by which fuel is 25 fed.

Having thus described my invention, what I claim, and desire to secure by Letters Patent, is—

1. The combination in a device of the class 30 described, of an ash-pit provided with an opening in the top thereof for establishing communication with the fire-pot of the device, a seat surrounding said opening, a boiler or furnace section mounted on said seat provided

with inwardly-projecting and upwardly-extending ribs terminating at a point removed from the bottom of said section thereby forming an enlarged chamber below said ribbed portion, lugs supported by said ash-pit projecting into the opening therein provided 40 with perforations, segmental fire-pot sections each arranged to be mounted on adjoining lugs and extend therebetween and be substantially positioned within said enlarged chamber.

2. The combination in a device of the class described, of an ash-pit provided with an opening in the top thereof for establishing communication with the fire-pot of the device, a seat surrounding said opening, a boiler 50 or furnace section mounted on said seat, a plurality of lugs each provided with a plurality of perforations supported by said ash-pit and projecting into the opening thereof, and a plurality of segmental fire-pot sections 55 each of which is provided with a plurality of downwardly-extending pins arranged to enter said perforations whereby said sections may be positioned about the interior of said fire-pot.

In testimony whereof I have hereunto set my hand in presence of two subscribing witnesses.

ALFRED G. CRIPPS.
